POST TOP LUMINAIRE UTILITY POLE

William J. Whatley, 2069 S. Macon Way,
Aurora, Colo. 80232

Filed Nov. 21, 1974, Ser. No. 525,921

Term of patent 14 years

Int. Cl. D26—03

U.S. Cl. D48—31

FIG. 1

FIG. 2

FIG. 3

FIG. 4

FIG. 1 is a view in elevation of a post top luminaire utility pole showing my design;

FIG. 2 is a view in elevation thereof rotated 45° about the longitudinal axis of the pole;

FIG. 3 is a top plan view thereof; and

FIG. 4 is a bottom plan view thereof.

I claim:

The ornamental design for a post top luminaire utility pole, as shown.
